UNITED STATES PATENT OFFICE.

JACOB SIIM MARCUSSEN, OF COPENHAGEN, DENMARK.

TABULATOR FOR TYPEWRITERS.

Application filed December 24, 1921. Serial No. 524,641.

To all whom it may concern:

Be it known that I, JACOB SIIM MARCUSSEN, a subject of the Kingdom of Denmark, residing at No. 96 Guldbergsgade, Copenhagen, N., Denmark, have invented certain new and useful Improvements in Tabulators for Typewriters, of which the following is a specification.

This invention relates to a tabulator for typewriters and consists of a system of levers by means of which the carriage may be released and permitted to move freely, the carriage being afterwards stopped at any predetermined point.

An embodiment of the invention is illustrated on the accompanying drawing.

Fig. 1 is a perspective view of the tabulator arranged on the carriage bed.

Fig. 2 is a plan view of part of the operating mechanism.

Fig. 3 is a detail view of part of Fig. 2 on an enlarged scale.

Fig. 4 is a cross section of the carriage bed and the operating and stopping mechanism on a line A—A of Fig. 3.

Fig. 5 is a cross section of the carriage bed and the operating and stopping mechanism on a line B—B of Fig. 3.

1 is the carriage bed plate above which are arranged a rack 2 and a releasing lever 3 having two pivotal points 4 about which it is adapted to rock, and also having upright end portions or handles 5, said lever 3 being kept in its place by means of a spring 22. At one end of the carriage bed and below this bed is arranged a key lever 6 having a finger piece or cap 7, a pivot point 8 and a short arm 9 passing upwards through a hole in the bed and meeting the end of one arm 10 of a sub-lever pivoted at its center, as indicated at 11, upon the bed plate 1. The opposite arm 12 of the sub-lever is provided with an upturned terminal lap or hook 13 which meets the lever 3.

At the underside of the bed plate 1 is arranged a movable stop 14 which is slidably mounted by means of two screws 16 moving in a groove 15 in the stop 14, the latter having a pair of struck-up lugs 17 passing up through an opening 18 in the bed plate 1 and embracing the lever arm 12.

At the back of the carriage frame and connected thereto is a bar 19 carrying one or more slidable tabulator stops 20, 21 which are fastened by means of screws 23.

When the tabulating mechanism is to be

used, the key lever 6 is pressed downward, the arm 9 thereby pressing against the arm 10 of the sub-lever, so that the latter is rocked and its hook 13, in turn, rocks the lever 3 and simultaneously disengages the usual pawl mechanism (not shown) from the rack 2, thereby releasing the carriage. At the same time the arm 12 presses against one of the lugs 17 and moves the stop 14 forward beneath the bed 1. The carriage now moves automatically until the stop 14 meets the first stop 20, where it stops and remains for the period wanted, the spring 22 moving the lever 3, the arm 12 and the stop 14 back into their original positions. A second depression of the key lever 6 will again release the carriage and move the stop 14 forward to engage the next stationary stop 21 etc.

In view of its plain and simple construction and slight weight the invention is specially applicable to portable typewriters, but may also in many cases be used with advantage by stationary typewriters.

Having now particularly described and ascertained the nature of my said invention I declare that what I claim is:

1. In a typewriter, the combination with a carriage bed over which a carriage is adapted to travel, letter-feed mechanism and carriage release mechanism; of a tabulating key lever mounted on said carriage bed; a sub-lever pivotally mounted on said bed and operated directly by said tabulating key lever; means carried by said sub-lever for directly operating said carriage release mechanism; stops mounted to move with the carriage; and a stop slidably mounted on said carriage bed and movable directly by said sub-lever into the path of travel of the carriage stops and concomitantly with release of the carriage.

2. In a portable typewriter, the combination with a carriage bed plate over which a carriage is adapted to travel, letter-feed mechanism and carriage release mechanism; of a tabulating key lever mounted on the carriage bed plate; a sub-lever mounted to pivot on a vertical axis on said bed plate and operated directly by said key lever and adapted to operate said carriage release mechanism; stops mounted to move with the carriage; and a sheet metal stop movably mounted on said carriage bed plate and having a pair of struck-up lugs embracing said sub-lever and by means of which the

sub-lever moves the movable stop to and from stopping position.

3. In a portable typewriter, the combination with a carriage bed over which a carriage is adapted to travel, letter-feed mechanism and carriage release mechanism; of a tabulating key-lever mounted on the carriage bed; stops mounted to move with said carriage; and a sheet-metal stop mounted 10 on said carriage bed to move transversely thereacross and in a horizontal plane and having a struck-up lug engaged directly and by said sub-lever by means of which the sub-lever moves the movable stop to 15 stopping position.

4. In a typewriter, the combination, with a carriage bed over which a carriage is adapted to travel and escapement mechanism for the carriage, of carriage release 20 mechanism including a releasing lever for the escapement mechanism; a tabulating key lever; a sub-lever pivotally mounted on the carriage bed and operated directly by said key lever, the sub-lever having a part 25 engageable with the releasing lever to actuate the same; stop mounted to move with the carriage; and a stop slidably mounted on the carriage bed and movable directly by the sub-lever with the path of the carriage stops and concomitantly with the actuation of the releasing lever.

5. In a typewriter, the combination of a

carriage bed plate over which a carriage is adapted to travel; a tabulating key lever pivotally connected thereto; a sub-lever 35 pivoted on said bed plate in position to be operated by the tabulating key lever; carriage-release mechanism including a releasing lever directly operated by the sub-lever; stops connected to move with the carriage; and a movable stop carried by the bed plate to be shifted by the sub-lever into and out of position for coaction with the first-named stops.

6. In a typewriter, the combination of a carriage bed plate over which a carriage is adapted to travel, said plate having a slot adjacent one end; a tabulating key-lever pivotally mounted below the bed plate and having a hook which projects upwardly through said slot; a sub-lever pivoted on said plate to move in a horizontal plane and having one end disposed in the path of said hook to be actuated thereby; carriage-release mechanism including a releasing lever positioned to be directly engaged and operated by the sub-lever; stops connected to move with the carriage; and a movable stop carried by the bed plate to be shifted by the sub-lever into and out of position for coaction with the first-named stops.

In testimony whereof I affix my signature.
JACOB SIIM MARCUSSEN.
